SLIDING CLOSURE AND SUSPENSION
SYSTEM THEREFOR

Abraham Grossman, Van Nuys, Calif.

Application January 16, 1950, Serial No. 138,915

11 Claims. (Cl. 20—52.2)

1

This invention relates to improvements in sliding closures and, more particularly, to sliding closures adapted for use as doors and windows in various types of structures.

To facilitate the disclosure of the construction and mode of operation of a closure constructed in accordance with my invention, the invention is exemplified as embodied in a door having a fixed sash and a movable sash but, of course, any number of movable and fixed sashes can be utilized in combination and it is obvious that the principles of the invention are equally applicable to both door and window construction.

A common deficiency of conventional sliding closures is the fact that such closures are so constructed that the entry of air and moisture into the structures with which they are associated is possible due to the difficulty of completely weather-stripping such movable sash structures by accepted methods.

It is, therefore, a primary object of my invention to provide a sliding sash closure which is characterized by great resistance to the ingress of air and moisture into the structure with which it is associated.

An additional object of my invention is the provision of a sliding closure in which the movable sash of the sliding closure is provided with resilient sealing means for preventing the ingress of air and moisture into the structure with which the sliding closure is associated. An associated object of my invention is the provision of a sliding closure for structures in which the movable sash component has the resilient sealing means positioned in recesses formed in the sliding closure, said resilient sealing means being carried in the recesses and moved concomitantly with the movement of the movable sash of the sliding closure.

Another object of my invention is the provision of a sliding closure, the movable sash of which is provided with a plurality of recesses to receive the aforementioned sealing means. These recesses protect the sealing means from injury and also permit the sealing means to be installed without the use of fasteners.

A further object of my invention is the provision of resilient sealing means for the movable sash of a sliding closure which is adapted, in addition to sealing the closure against air and moisture, to orient the movable sash of the closure in reference to the track means upon which the movable sash is supported and upon which it moves.

A further object of my invention is the provi-

2

sion of resilient sealing means for the movable sash of the sliding closure which serves to absorb shock loads imposed upon the movable sash by sudden gusts of wind and accidental blows to prevent the shattering of the glass supported in the movable sash.

Another object of my invention is the provision in the frame of the sliding closure of positioning means adapted to supplement the action of the resilient sealing means in orienting the movable sash with reference to the frame and also to supplement the action of the sealing means in its weather-stripping and shock absorbing functions. An associated object of my invention is the provision of positioning means of the aforementioned type which is resilient in nature and which contacts the entire length of the movable sash at the top, bottom and side thereof.

Another common defect of conventional sliding closures is the fact that it is frequently very difficult to wash the glass mounted in the sliding closure, particularly if the movable sash of the sliding closure is, in the case of a window, accessible from the interior of the structure only or, in the case of a door, where the movable sash is relatively high and accessible only by specialized cleaning instruments.

A further object of my invention is the provision of a sliding closure for structures in which the movable sash is so mounted in the frame of the closure that it may be readily lifted from its engagement with the frame to facilitate the cleaning thereof. The construction of the movable sash permits its easy removal from engagement with the frame of the closure and permits access to the resilient sealing means of the movable sash and to the component parts of the frame of the closure to permit the adjustment, servicing or replacement thereof.

After conventional closures have been installed in a structure, sagging of the head of the opening in which the closure is installed frequently occurs, placing bending loads upon the upper portion of the frame of the closure which cause the downward deflection of the upper portion of the frame and prevent the free movement of the movable sash of the closure within the frame. In such cases, it is frequently necessary to remove the closure from the opening and to reinforce the structure around the opening before the closure can be replaced.

A further object of my invention is the provision of a slidable closure for the openings in a structure in which the frame thereof, and particularly the upper portion of the frame, is ad-

justable to permit the downward sagging of the structure surrounding the frame to be compensated for to prevent the binding of the movable sash of the closure in the frame. This adjustment of the frame may be readily accomplished by removing the movable sash from the frame in the above-described manner.

An additional object of my invention is the provision of a sliding closure for structures, the frame of which can be mounted in an opening in the structure with a minimum of fastening means, thus greatly facilitating the installation of the closure.

An additional object of my invention is the provision of a sliding closure for structures which is composed of a relatively small number of interchangeable parts which can be used to serve similar functions in different portions of the closure structure. This materially reduces the cost of fabricating the closure and facilitates the shipping and the installation of the closure.

Other objects and advantages of my invention will be apparent from the following specification and the accompanying drawings, which are for the purpose of illustration only, and in which:

Fig. 1 is a perspective view showing the installation in a structure of a door constructed in accordance with my invention;

Fig. 2 is a vertical sectional view taken on the broken line 2—2 of Fig. 1;

Fig. 3 is a longitudinal sectional view taken on the broken line 3—3 of Fig. 2;

Fig. 4 is a fragmentary, partly sectional view taken on the broken line 4—4 of Fig. 2;

Fig. 5 is a fragmentary, partly sectional view taken on the broken line 5—5 of Fig. 2; and

Fig. 6 is a detail of a component part of the frame structure of the closure.

Referring to the drawings and particularly to Fig. 1 thereof, I show a closure 10 for an opening 11 in a structure 12, the closure 10 being exemplified as a door 13 having a fixed sash 14 and a movable sash 15. Although my invention is described as being embodied in a door 13 having a fixed sash 14 and a movable sash 15, I do not intend that my invention be limited to the combination of a fixed sash with a movable sash since it is obvious that the use of a fixed sash can be dispensed with and any number of movable sashes be used in combination. It is also possible to use one movable sash or more than one movable sash in conjunction with a plurality of fixed sashes.

The opening 11 in the structure 12 is defined at the top thereof, Fig. 2, by a head 17 to which is attached by suitable fasteners, not shown, a lintel 18, the base of the opening being defined by a sill 19, said lintel and said sill being preferably formed of wood or similar material. The sides of the opening 11 in the structure 12, Fig. 3, are defined by jambs 20. The lintel 18, the sill 19 and the jambs 20 together define a substantially rectangular opening to which is secured and in which is positioned a frame 22 of the sliding closure which is the subject of my invention.

The frame 22 includes a top member 23 and a bottom member 24, Fig. 2, which are connected to each other by side members 25 and 26, Fig. 3. The top member 23 is constituted by an elongated channel member 29, preferably extruded from aluminum, and having formed integrally therewith at the inner edge thereof a downwardly depending top track 30. The channel member 29 defines a channel 31 in which is adapted to be positioned a plurality of suspension clips 32

which are spaced along the channel 31 at predetermined intervals and which are formed of stainless steel or similar material. A plurality of openings 33 is formed in the channel member 29 adjacent the top track 30, said openings being adapted to register with oppositely positioned openings 34 and 35 formed in the suspension clip 32. Suspension bolts 36 are inserted through the openings 33, 34 and 35 and screwed into the lintel 18 to support the channel member 29 at the top of the frame 22.

The use of the suspension clips 32 in conjunction with the channel member 29 permits the top frame member 23 to be rigidly fastened to the under side of the lintel 18 at the inside edge of the channel member 29 alone, the clip 32 serving to distribute the load through the channel member 29. As will be noted, the top frame member 23 is thus fastened to the lintel 18 by a minimum number of bolts which are juxtaposed to the top track 30 and which are readily accessible from the interior of the structure in a manner which will be described in greater detail below.

It will be noted that a gap 37 is permitted to exist between the top of the channel member 29 and the bottom of the lintel 18. It has been discovered that, particularly where the openings in the structure are of relatively great length, the lintel 18 bends as the structure settles, causing it to sag and to impose a load upon the top frame member, thus preventing the proper functioning of the movable sash 15 of the closure 10. When such sagging of the lintel 18 due to the settling of the structure 12 occurs in a structure equipped with the closure 10 of my invention, the sagging of the lintel 18 is accommodated by taking up the suspension bolts 36 by screwing them into the lintel 18 a sufficient distance to accommodate the downward deflection of the lintel. Because of the accessibility of the comparatively few suspension bolts utilized in suspending the channel member 29, this adjustment can be accomplished with relative ease and the necessity for completely removing the closure from the opening or for reworking the frame of the closure is eliminated. This is a very important feature of my invention.

The bottom frame member 24 is constituted by an elongated channel member 39 having a downwardly sloping upper surface 40 to facilitate the run-off of moisture and having legs 41 and 42 adapted to support it upon the sill 19. The inner leg 41 is provided with a right angle flange 43 in which is formed a plurality of openings 44 adapted to receive screws 45 which secure the channel member 39 to the sill 19. A mastic sealing compound 46 may be utilized to seal the top and bottom channel members 29 and 39 to the structure 12 against the ingress of air and moisture. Formed integrally upon the inner edge of the bottom channel member 39 and projecting upwardly therefrom, is a bottom track 50 which, in conjunction with the top track 30, supports the movable sash 15 of the door 13 in a manner which will be described in greater detail below.

The side frame members 25 and 26 are constituted by channel members 51 and 52, the configuration of which is identical with that of the top channel member 29, the channel members 51 and 52 being attached to the jambs 20 of the opening 11 by means of clips 53 and fasteners 54 passing through said channel members 51 and 52 and clips 53. Shims 55 interposed between the channel members 51 and 52 and the jambs 20 serve to adjust the side members 25 and 26 in

reference to the opening 11 in the structure 12. Each of the channel members 51 and 52 has laterally projecting engagement means 56 formed integrally therewith, for a purpose which will be described in greater detail below. Juxtaposed to the engagement means 56 are resilient bumpers 57 which are secured in openings in the channel members 51 and 52. The channel members 29, 39, 51 and 52 may be fastened to each other by any conventional means, such as welding. The use of identical channel members 29, 51 and 52 to form the top and side members 23, 25 and 26 materially reduces the cost of fabricating the frame 22 of the closure 10.

The fixed sash 14 includes top and bottom rails 58 and 59 connected to each other by stiles 60 and 61, the top and bottom rails 58 and 59 and the stiles 60 and 61 being formed from lengths of extrusion 63 having identical configurations. Since the extrusions forming the fixed sash 14 are identical in configuration, a description of the extrusion which constitutes the stile 60, Fig. 3, will suffice as a description of the extrusion constituting the top and bottom rails 58 and 59 and the other stile 61.

The length of extrusion 63 which forms the stile 60 includes a closed channel 64 having juxtaposed thereto a channel 65 provided with a longitudinal opening or slot 66. Formed integrally with the body of the extrusion 63 is a laterally projecting flange 67 which is spaced from a wedge-shaped key 68 formed integrally with the extrusion 63 and oppositely disposed to the flange 67. The stile 60 of the fixed sash 14 is secured to a rib 69 projecting from and formed integrally with the side frame member 25. The opposite stile 61 is fastened to an angle 70 which extends between the bottom frame member 24 and the top frame member 23. The top rail 58 of the fixed sash 14 is secured to a downwardly projecting rib 71 formed integrally with the top frame member 23 and the bottom rail 59 is mounted upon an elongated supporting channel 72 which rests upon the sloping upper surface 40 of the bottom frame member 24 and which is coextensive with the bottom rail 59. The primary function of the channel 72, in addition to supporting the fixed sash, is to prevent ingress of water into the structure by presenting a barrier to the passage thereof under and between the moving and fixed sashes. The upper surface of the longitudinal supporting channel 72 is provided with upwardly projecting detent means 73 which are received in the opening 66 provided in the channel 65 of the extrusion 63 and the open end of the channel 72 is closed by means of the angle 70 which extends between the bottom frame member 24 and the top frame member 23.

A sheet of glass 74 is mounted in the frame of the fixed sash 14 by means of glass retaining means 75 having keys 76 mating with the keys 68 on the extrusions 63 and pressure arms 77 adapted to force the edges of the sheet of glass 74 against mounting strips 78 preferably formed of mastic impregnated sponge rubber.

The movable sash includes top and bottom rails 80 and 81 and stiles 82 and 83, the top and bottom rails 80 and 81 and the stiles 82 and 83 being formed of lengths of extrusion 63 identical in all respects with the lengths of extrusion 63 constituting the frame of the fixed sash 14. However, the extrusion 63 utilized in the bottom rail 81 of the movable sash 15 is modified to a certain extent for a purpose which will be described in greater detail below.

The top rail 80 of the movable sash 15, Fig. 2, is constituted by a length of extrusion 63, the channel 65 therein providing a recess 85 which extends the length of the top rail 80 and which is adapted to receive and has positioned therein an elongated, resilient sealing member 86 formed of spring sheet stock and having a central, substantially U-shaped portion 87 and downwardly directed centering arms 88. The U-shaped portion 87 of the resilient sealing member 86 provides a longitudinal groove or recess 89 which is adapted to receive the lower end of the top track 30. The top rail 80 of the movable sash 15 is thus slidably mounted upon the track 30 through the intermediary of the resilient sealing member 86 and a seal is created between the lowermost end of the track means 30 and the U-shaped portion 87 of the resilient sealing member 86 to prevent the ingress of air and moisture past the top rail 80 of the movable sash 15. It will be noted that the lowermost end of the top track 30 is maintained in the center of the top rail 80 by its position in the groove 89 provided by the U-shaped portion 87 of the resilient sealing member 86, the resilient sealing member thus serving to properly orient the top rail 80 of the movable sash 15 in respect to the track means 30. In addition, when a shock or undue load is placed upon the movable sash, as by means of a gust of wind or an accidental contact with the movable sash 15, the centering arms 88 are able to deflect sufficiently to absorb the shock and to permit the momentary deflection of the movable sash 15 to prevent injury to the sash. Of interest also is the fact that the contact of the top track 30 with the resilient sealing member is substantially a point-to-point contact and frictional drag induced by the sliding contact of the resilient sealing member 86 with the track 30 is maintained at a minimum, thus permitting the easy movement of the movable sash 15. The sealing means 86 is coextensive with the top rail 80.

Secured to the under side of the channel 29 constituting the top frame 23 by means of an elongated extrusion 90, which is disposed upon the under side of the top frame member 29, and secured to the downwardly projecting rim 71 thereof between the angle 70 and the side frame member 26, is a positioning means 91 exemplified as an elongated spring 92 having a resilient arm 93 impinging upon the outer edge of the top rail 80 of the movable sash 15 and making a point-to-point contact therewith. The positioning means 91 serves to supplement the orienting action of the resilient sealing member 86 and also serves as an auxiliary means of preventing the entry of air and moisture into the structure past the top rail 80 of the movable sash 15. Of course, when the movable sash is subjected to undue and sudden loads, the deflection of the movable sash as permitted by the resilient sealing member 86 causes the simultaneous deflection of the resilient arm 93 of the positioning means 91.

The bottom rail 81 of the movable sash 15 is formed from a length of extrusion 63, the channel 65 constituting a recess 94 into which the bottom track member 50 projects upwardly through the opening 66. The dividing wall between the channel 64 and the channel 65 has been removed and positioned upon spindles 95 pressed into the side walls of the extrusion 63 are rollers 96 which engage the upper end of the bottom track 50. The rollers 96, as best seen in Fig. 5,

project upwardly into the channel 64 through openings 97 formed in the elongated, resilient sealing means 86 which is positioned in the recess 94 and which engages the sides of the roller 95 to prevent the ingress of air and moisture into the interior of the structure. In addition, it will also be noted, Fig. 2, that the resilient sealing member 86 also contacts the sides of the bottom track 50 and the area of the extrusion 63 adjacent to the opening 66 therein, to insure that no air or moisture will enter the structure past the bottom rail 81 of the movable sash 15.

When it is desired to remove the movable sash 15 from contact with the top track 30 and the bottom track 50 to facilitate the cleaning thereof, the adjustment of the top frame member 23 to compensate for the downward deflection of the lintel 18 or to permit the servicing and/or repair of any of the portions of the closure, the movable sash is lifted vertically to cause movement of the top track 30 into the groove 89 and to lift the rollers 95 out of contact with the track 50 and to disengage the track 50 from the resilient sealing member 86 and the opening 66 in the extrusion 63. When this has been accomplished, the movable sash 15 can be lowered to disengage the top track 30 from the groove 89 in the resilient sealing member 86. The movable sash 15 is thus, in two movements, completely freed from engagement with the top and bottom tracks 30 and 50 respectively and may be suitably positioned to facilitate the cleaning of the sash. As is obvious, when the sash is removed from the tracks 30 and 50, the suspension bolts 35 are readily accessible for permitting the adjustment of the top member 23 of the frame 22 to compensate for the vertical deflection of the lintel 18. In addition, should it be necessary to repair or service the resilient sealing members 86 embodied in the top and bottom rails 80 and 81, it is only necessary to press the U-shaped intermediate portions 87 thereof together to pass the resilient sealing members 86 through the openings 66 into the top and bottom rails 30 and 81 in order to completely disengage the resilient sealing members from the top and bottom rails.

The stiles 82 and 83 of the movable sash 15, Fig. 3, are formed from lengths of extrusion 63 and the longitudinal channels 65 of the stiles are adapted to engage the engagement means 56 formed upon the side members 25 and 26 of the frame 22. Positioned in the recess 65 of the stile 83 is an elongated sealing member 86 which is identical in all respects with the previously discussed sealing members 86 of the top and bottom rails 80 and 81 and which includes the U-shaped central portion 87 and the centering arms 88, the U-shaped central portion 87 defining a longitudinal groove 89 adapted to receive the engagement means 56 of the side member 26 of the frame 22 when the movable sash 15 is closed thereupon, as best shown in Fig. 3 of the drawings.

When the movable sash is in either the extreme open or extreme closed position, the bumpers 57 mounted upon the side members 25 and 26 of the frame 22 are contacted by the stiles 82 and 83 respectively and also serve to prevent damage of the movable sash 15 when the movable sash is closed or opened with undue force. Mounted upon the side frame member 26 and adapted to engage the outer surface of the stile 83 when the movable sash 15 is moved into closed position and into engagement with the engagement means 56,

is an auxiliary sealing means 99 constituted by an elongated, vertically positioned resilient weather stripping 101 which is secured to the side frame member 26 by means of an extrusion 102 which is, in turn, fastened to the vertical frame member 26. The auxiliary sealing means 99 supplements the action of the resilient sealing means 86 mounted in the recess 65 of the stile 83 and prevents ingress of air and moisture into the structure with which the closure is associated.

Secured to the stile 82 of the movable sash is an engagement means 104 constituted by a vertically positioned extrusion 105 having a leg 106 adapted to engage with engagement means 107 constituting a portion of the angle 70. Thus, as best shown in Fig. 3, when the movable sash 15 is in the closed position the leg 106 of the engagement means 104 engages the engagement means 107 to form a seal therebetween to prevent the ingress of air and moisture between the stile 82 of the movable sash 15 and the stile 61 of the fixed sash 14. Secured to the stile 61 of the fixed sash 14 is a positioning means 109 for the engagement means 104 and 107 which is adapted to impinge upon the end of the leg 106 of the engagement means 104 and which is adapted to force the engagement means 104 into closer contact with the engagement means 107. The positioning means 109 is constituted by an elongated spring 110 secured to and disposed between the angle 70 and the stile 61. In this manner, the entry of moisture and air between the stile 61 of the fixed sash and 82 of the movable sash is obviated.

Positioned in the frame of the movable sash 15, as constituted by the top and bottom rails 80 and 81 and the stiles 82 and 83, is a sheet of glass 112 which is retained therein by means of glass retaining means 75, the sheet of glass 112 being positioned between the glass retaining means 75 and strips 78 of mastic impregnated sponge rubber sealing material.

As may be observed from Figs. 2 and 4 of the drawings, when the movable sash 15 is in closed position a gap 113 exists between the under side of the movable sash 15 and the edge of the supporting channel 12 which would permit the entry of air and moisture into the interior of the structure if some means were not provided for automatically closing off the gap 113. To prevent the ingress of air and moisture through the gap 113, there is mounted upon a base 114 by means of a screw 115 a weather block 116 consisting of a resilient spring 117 which impinges on the under side of the movable sash 15 and thus closes off the gap 113 to prevent the ingress of air and moisture therethrough, as best seen in Figs. 2, 3 and 4.

I thus provide by my invention a sliding closure for structures which is characterized by extreme simplicity of construction and by the utilization of relatively few, interchangeable parts. A window or door constructed in accordance with my invention, when installed in a structure, will prevent the ingress of air and moisture into the structure since sealing means to prevent such ingress have been provided at all points of the closure where such entry of air and moisture might take place.

An additional feature of my invention is the fact the sealing means embodied therein serve also to orient the movable sash of the closure with respect to the frame thereof and to absorb shock loads imposed thereupon to prevent breakage of the glass supported in the movable sash. Also of note is the fact that the movable sash of

the closure can be very easily translated because the sash is supported upon the frame of the closure by point-to-point contact and frictional losses occasioned by frictional drag are reduced to a minimum.

Also of importance is the fact that the movable sash of the sliding closure can be readily removed from the frame of the closure in which it is mounted to facilitate the washing of the sheet of glass supported in the movable sash or to permit the servicing or adjustment of the component parts of the movable sash or the closure frame. The adjustability of the frame of the closure to compensate for sagging in the structure with which the closure is associated is also an important feature since it insures that the movable sash of the closure will not be subjected to bending loads which would cause it to bind and prevent free movement thereof. Generally speaking, a door or window when constructed in accordance with my invention is characterized by extreme resistance to the entry of air and moisture therewith, by ease of maintenance and repair, by extremely easy movement of the movable sash of the door or window, by eliminating any contact of the sash with rigid metal in operating or closed positions, and by facility of installation and construction.

Although I have shown and described a preferred embodiment of my invention for the purpose of illustrating the construction and mode of operation thereof, it is obvious that changes, modifications and alterations may be made in the specific details of said construction and I, therefore, do not desire to be limited to said specific details but prefer, rather, to be afforded the full scope of the following claims.

I claim as my invention:

1. In a closure, the combination of: a frame, said frame including top and bottom frame members and track means on said top and bottom frame members, said top frame member having an elongated resilient strip constituting positioning means secured thereto adjacent and spaced from said track means; and a movable sash, said movable sash having a top rail and a bottom rail, and longitudinal recesses in said top and bottom rails having deposited therein resilient sealing means for receiving said track means, said positioning means impinging upon said top rail of said movable sash and being of a length equivalent to the length of said movable sash to prevent the misalignment of said movable sash with said track means of said top frame member.

2. In a closure, the combination of: a frame, said frame including top and bottom frame members and track means on said top and bottom frame members; a fixed sash secured between said top and bottom frame members, said fixed sash having a top rail and a bottom rail and stiles connecting said top and bottom rails, one of said stiles of said fixed sash having engagement means thereupon; a movable sash, said movable sash having top and bottom rails and stiles connecting said top and bottom rails, one of said stiles having engagement means thereupon adapted to interengage with the engagement means upon said one stile of said fixed sash; and positioning means on said fixed sash for urging said engagement means of said fixed sash and of said movable sash into closer contact with each other.

3. In a closure, the combination of: a frame, said frame including top and bottom frame members and side members disposed between said top and bottom frame members, said top and bottom

frame members having track means formed thereupon and said side members having engagement means formed integrally therewith; a sash positioned between said top and bottom frame members; and a movable sash, said movable sash having top and bottom rails and stiles interconnecting said top and bottom rails, said top and bottom rails and said stiles having longitudinal recesses formed therein, said recesses in said top and bottom rails having deposited therein elongated, resilient sealing means for engaging said track means and the recess in one of said stiles having elongated resilient sealing means deposited therein for engaging one of said engagement means on one of said side members.

4. In a closure, the combination of: a frame, said frame including top and bottom frame members and side members disposed between said top and bottom frame members, said top and bottom frame members having track means and said side members having engagement means formed thereupon; a fixed sash secured between said top and bottom frame members; a movable sash, said movable sash having top and bottom rails and stiles, said top and bottom rails and said stiles having recesses formed therein, said recesses in said top and bottom rails and in one of said stiles having elongated, resilient sealing means deposited therein, said sealing means in said rails engaging said track means and said sealing means in said stile engaging one of said engagement means of said side members; and auxiliary sealing means, consisting of an elongated resilient strip, upon said one side member for contacting said stile.

5. In a closure, the combination of: a frame, said frame including top and bottom frame members and side members disposed between said top and bottom frame members, said top and bottom frame members having track means and said side members having engagement means formed thereupon; a fixed sash secured between said top and bottom frame members; a movable sash, said movable sash having top and bottom rails and stiles; engagement means on a stile of said fixed sash and on a stile of said movable sash to enable said engagement means to overlap each other when said movable sash is moved to close said frame; and resilient weather block means secured to said bottom frame member adjacent the engagement means of said fixed sash to prevent ingress of air and moisture by contacting the lowermost ends of said engagement means when said engagement means are overlapped.

6. In a closure, the combination of: a frame, said frame including top and bottom frame members and track means on said top and bottom frame members; a movable sash, said movable sash having a top rail and a bottom rail, said top and bottom rails having elongated recesses formed therein for receiving said track means, the side walls of said recesses having retaining means thereupon; and elongated, resilient sealing means positioned in said recesses, said sealing means having portions engageable with said retaining means for releasably securing said sealing means in said recesses and portions contacted by said track means for sealing engagement with said track means.

7. In a closure, the combination of: a frame, said frame including top and bottom frame members and track means on said top and bottom frame members; a movable sash, said movable sash having a top rail and a bottom rail, said top and bottom rails having longitudinal track-

receiving slots formed therein which communicate with longitudinal recesses in said rails, said slots being defined by lateral extensions of the walls of said recesses; and elongated resilient sealing means positioned in said recesses, said sealing means having lateral resilient arms engageable with said extensions for releasably securing said sealing means in said recesses and maintaining portions of said sealing means in sealing engagement with said track means.

8. In a closure, the combination of: a frame, said frame including top and bottom frame members and track means on said top and bottom frame members; a movable sash, said movable sash having a top rail and a bottom rail, said top and bottom rails having longitudinal, track-receiving slots formed therein which communicate with longitudinal recesses in said rails, said slots being defined by lateral extensions of the walls of said recesses; and elongated resilient sealing means positioned in said recesses, said sealing means having substantially U-shaped, central sealing portions for engagement with said track means and oppositely disposed lateral arms engageable with said extensions for releasably securing said sealing means in said recesses.

9. In a closure, the combination of: a frame, said frame including top and bottom frame members and track means on said top and bottom frame members; a movable sash, said movable sash having a top rail and a bottom rail, said top and bottom rails having elongated recesses formed therein for receiving said track means, the side walls of said recesses having retaining means thereupon; and elongated, resilient sealing means positioned in said recesses, said sealing means having substantially U-shaped, central sealing portions for engagement with said track means and oppositely disposed lateral arms engageable with said retaining means for releasably securing said sealing means in said recesses.

10. In a closure, the combination of: a frame, said frame including top and bottom frame members and track means secured to said top and bottom frame members; a movable sash, said movable sash having a top rail and a bottom rail, said top and bottom rails having elongated recesses formed therein; and elongated resilient sealing

means positioned in said recesses and having substantially U-shaped, resilient central portions whose bases are disposed on the bottoms of said recesses and whose open ends are juxtaposed to the openings into said recesses, the top frame track means having only its lowermost portion disposed in the opening in said top rail recess and in spaced relation with the bottom thereof for engagement with the open end of said U-shaped portion of said resilient means to permit said sash to be lifted bodily to urge said top frame track means downwardly into said top rail recess to release said bottom rail recess from said bottom rail track means and thus to release said sash from said frame.

11. In a closure, the combination of: a frame, said frame including top and bottom frame members and track means on said top and bottom frame members; a movable sash, said movable sash having a top rail and a bottom rail, said top and bottom rails having elongated recesses formed therein for receiving said track means; elongated resilient sealing means positioned in said recesses, said sealing means including central, substantially U-shaped sealing portions and lateral positioning arms, the U-shaped portions of said sealing means in said bottom rail recess having a plurality of spaced openings therein; and a plurality of rollers disposed in said bottom rail recess in said openings whose sides are engaged by said U-shaped portions to seal them against the influx of air and moisture.

ABRAHAM GROSSMAN.
